BRACKET FOR A BATHROOM FIXTURE

Peter Ganine, Los Angeles, Calif., assignor to Textron,
Inc., Providence, R.I., a corporation of Rhode Island

Application February 12, 1959, Serial No. 54,573

Term of patent 14 years

(Cl. D4—3)

FIG. 3.

FIG. 4.

FIG. 5.

FIG. 6.

The essential features of the design reside in the portions shown in full lines.

I claim:

The ornamental design for a bracket for a bathroom fixture, substantially as shown and described.
